CLAIM

We claim the ornamental design for an electronic communications device, as shown and described.

DESCRIPTION

FIG. 1 is a perspective view of an electronic communications device showing our design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines in the drawings show portions of the electronic communications device that form no part of the claimed design.

1 Claim, 5 Drawing Sheets
